(54) GRIST MILL, & SPRIAL WATER WHEEL

(76) Inventor: Alexander Temple

Alexander Temple - Brookfield, Ohio.
Letters Patent.

Dated December 11th 1829.

The Schedule referred to in these Letters Patent & making part of the same, containing a description in the words of the said Alexander Temple himself, of his improvement in the Grist Mill, & horizontal Spiral Water Wheel.

Be it known that I, Alexander Temple of Brookfield, in the County of Franklin, State of Ohio, have invented a new & useful improvement in the Grist Mill which is described as follows, viz:

1st The improvement consists of three stones, two bed or fast stones let into Timbers or Bearers, the one made fast to the frame; the other to move on grooves on the side girts of the frame. The runner is in the form of a double cone, with a mandril or spindle passing thru the bed stones & bearers on which the runner is made fast with two choppers or breakers at each end of the runner say 9 $\frac{1}{2}$ or 9 in. in diameter to be of steel or other metal, the choppers or conveyors to the runner may be larger at the end adjoining the runner with spiral lines to break & convey the grain to the runner, & bed stones to be dressed with spiral lines, say 6 or 7 leading furrows for a stone one foot four inches, with a draft of one inch at the centre, & dressed as other mill stones with Quarter Draft. These stones are moved by bolts with screws & bars, & each which passes thru the bearers & end of the frame to close them to the runner.

2nd The mandril or spindle to be made of Iron, say one inch at a half in diameter, with squares to fasten the pulley & choppers, ears &c. with the ends of steel, where it meets the tempering screw. The grain which passes from the hopper by shovels moved by rods through the bottom of the shovels down below the val cans on the mandril is conveyed to the centre of the choppers at the end of the runner by a passage in the bed stones, where it joins the bearers or Timbers.

Two temporary screws or levers, may be applied for setting back the ported bed stone if required.

The curb or hoop for confining the flour around the stones, may be made of sheet iron, having a cavity for the meal spout, the full space between the fast stones, which is the straight part of the runner. This mill is intended to grind all kinds of grain, working

from the centers, with two feeders from one hopper. The revolution of the stone is thought best at 25 revolutions in a minute.

The horizontal Spiral Water-Wheels with its forebay, directors & shoots are as follows: viz: The wheel or block to be about 3 inches on its edge at the raised at the shaft in the form of a cone, the buckets to be 12 $\frac{1}{2}$ inches wide in a circular form placed on an angle of about 60 degrees, the circle larger below, extending so far as to make the issues 2 inches wide on a wheel for 1 $\frac{1}{2}$ foot head of water, the issues reduced as the head may be, $\frac{1}{8}$ of an inch to every additional foot of head for 6 feet above 6 feet reduce the buckets in width; the wheel to be about 4 ft. in diameter, motion about 68 revolutions in a minute, when applied to a horizontal run of stems in common mills.

The gearing to be the same as in other mills & the mill may be moved by water, steam, or animal power.

What I claim as my invention which I wish to secure by Patent is

1st The double conical stone, or other materials, with the two breakers working in corresponding hollow cones or cones.

2nd The improvement in the water-wheels before described, that is in the manner of shaping & placing the buckets on the horizontal wheels, with the manner of letting the water on & off the wheel, preventing the ill effects of back water.

3rd In the manner of moving the damsel or shaking rod by means of an oval case placed on the mandril or spindle.
